UNITED STATES PATENT OFFICE.

MACK CARLTON BARRY, OF ATLANTA, GEORGIA.

RAPID-FIRE GUN.

1,233,165.

Specification of Letters Patent.

Patented July 10, 1917.

Application filed March 28, 1916. Serial No. 87,204.

To all whom it may concern:

Be it known that I, MACK C. BARRY, a citizen of the United States, and a resident of Atlanta, in the county of Fulton and 5 State of Georgia, have invented a certain new and useful Improvement in Rapid-Fire Guns, of which the following is a specification.

My present invention relates generally to 10 small arms, and more particularly to a rapid fire gun, my object being to provide certain improvements in the construction and operation of such devices whereby to promote more ready and quick handling and effective 15 use thereof, as outlined in the following description, reference being made to the accompanying drawings illustrating the preferred form of my invention and forming a part of this specification, and in which— 20 Figure 1 is a perspective view illustrating the complete gun in position ready for operation.

Fig. 2 is a view partly in side elevation, 25 of the upper portion of the gun, one of the barrels being broken away and in section through its breech portion.

Fig. 3 is an enlarged sectional view 30 through the upper portion of the tripod, stand, and the gun frame.

Fig. 4 is a horizontal section taken substantially on line 4—4 of Fig. 3.

Fig. 5 is a detail perspective view of one 35 of the breech blocks and its plunger, and the guide for the latter.

Fig. 6 is a detail perspective view illustrating a portion of one of the hammers and its locking dog.

Referring now to these figures, my invention preferably includes a tripod support, the legs 10, 11, and 12 of which are pivotally connected at their upper ends, by 40 pivot bolts 14, beneath the upper horizontal platform 15, one leg, the forward leg 12 in use, being engaged by a spring 16 extending between the same and a bearing block 17 depending from the platform 15, in order to hold the leg 12 outwardly in position as the operator seats the tripod, so that adjustment of only the two rear legs 10 and 11 45 which the operator can conveniently reach, is necessary.

Swiveled upon the platform 15 of the tripod, by a central king bolt 18, is a plate 19 having upstanding side ears 20 to which 50 the lower central portion of the gun frame

21 is pivoted by pivots 22, thus adapting the gun frame to forward and rear swinging movement in addition to the swiveled movements thereof in a horizontal plane upon the king bolt 18. 60

The gun frame 21 just above mentioned has a forward portion 23 constituting substantially a breech housing and having supporting guides 24 at its upper end for the several barrels 25 of the gun, and is provided with a rearwardly extending portion 26 and with an intermediate upper support for the magazine or cartridge box 27, the latter of which is preferably provided with a hinged top 28 and with its lower end opening downwardly at the rear of the breeches 29 of the several barrels 25, it being noted that the latter are arranged in horizontal alignment as seen in Fig. 1. 65

The gun frame 21 supports intermediate 70 transverse shafts 30 and 31, respectively carrying the several hammers 32 and the several hammer locking dogs 33, while the rearward extension 26 of the said frame supports a transverse operating shaft 34 and 75 its forwardly extending portion 23 supports a magazine controlling shaft 35. 80

Each of the several hammers 32 swings forwardly and rearwardly with the shaft 30 and is provided with a forwardly projecting lug 36 which the respective dog 33 engages as particularly shown in Fig. 2 to hold the hammer in its rearmost position, the several dogs 33 being movable with their shaft 31, at one end of which is an upright 85 arm 37, the upper end of which is engaged by one end of a rearwardly projecting spring 38, the rear end of which spring is attached to a portion of the frame 21 so as to normally move the dogs 33 rearwardly toward 90 engaged position, arm 37 being also pivotally connected to the forward end of a rod 39, the rear end of which is guided in an upstanding bracket 40 and is adapted for engagement by the upper forwardly extending 95 nose 41 of the operating lever 42 which latter is intermediately secured upon the operating shaft 34. 100

The upper end of each of the hammers 32 operates against the rear end of the respective firing pin 43 normally held in rearmost inoperative position by its controlling spring 44 and slidably mounted axially through its respective breech block 45. 105

Each of the breech blocks 45 is offset in 110

3 a vertical direction from the forward end 10 of its respective plunger 46 to which it is fast, and preferably integral as shown in Fig. 2. The rear end of each of the said plunger 46, which passes through its respective guide recess 47 in a bracket 48 up-standing from the rear extension 26 of the gun frame 21, is connected by links 49 to an extension 50 of the operating shaft 34, it being noted from full lines in Fig. 2 that 15 these parts 49 and 50 are longitudinally alined with one another when the plunger 46 is at its forward position to bring the breech block 45 in the firing position.

15 The lower portion of the breech 29 of each 20 of the barrels 25, as indicated at 51, is hinged at its forward end at 52 to permit its rear end to swing downwardly and discharge the shells, and is controlled in its movement through a pair of links 53 and 54, the latter of which is secured to the before mentioned shaft 35, it being noted that, 25 when the movable breech piece 51 is in its upper operative position, the links 53 and 54 are in longitudinal alinement. The shaft 35 has at one end a rigid arm 55 pivotally connected by a rod 56 to the operating lever 42.

30 Thus, in operation, the lower free end of the operating lever 42 is thrust forwardly after firing which simultaneously withdraws the several breech bolts 45, in the rearward movement of which the several hammers 32 are moved rearwardly until engaged by the 35 spring controlled dogs 33 and held in their rearmost cocked positions as shown in Fig. 2. Also at the same time the several movable breech pieces 51 are moved downwardly, permitting the shells to fall out of the 40 breech. When the several breech blocks 45 are withdrawn, fresh cartridges descend from the magazine or cartridge box 27, and when the lower free end of the lever 42 is drawn rearwardly, these cartridges are thrust into 45 the breech as the several breech pieces are closed. During this movement also the upper nose 41 of the lever 42 moves forwardly against the rear end of rod 39 and slightly rotates shaft 31 so as to withdraw the several dogs 33 and release the several hammers 32, each of which is provided further with a rearwardly projecting lug 57 engaged by a main spring 58 which, upon the 50 release of the hammer, forces the same forwardly against the firing pin 43.

55 For swinging the entire gun frame 21 up and down upon its pivot 22 and horizontally upon the king bolt 18, a lever 59 is provided, pivotally connected at its upper 60 end at 60 to lower rearwardly projecting portions 61 of the said frame, said lever being provided with an intermediate recess 62 which normally receives one edge of the upper platform 15 of the tripod frame, to 65 hold the frame 21 level, when the lever 59

is turned down and in vertical position, as shown in Figs. 1 and 2. At the extreme upper end of the lever 59 is a sliding locking piece 63 having limited movement on the lever and engageable beneath a rigid inclined extension 64 of the gun frame 21 so as to lock the lever 59 in raised position, as best seen in Fig. 3, in connection with the gun frame 21 and thus enable convenient control of the movements of such frame. 70

75 From the foregoing it is obvious that the mechanisms of the several barrels 25 may be controlled as readily and expeditiously as one barrel and that, from the disclosure, the numbers of barrels may greatly 80 vary dependent upon the particular uses for which the gun is designed, for instance, whether for offense or defense, and if for defense, whether the defensive works are of temporary or permanent nature, it being, 85 of course, obvious that the less number of barrels there are to the gun, the lighter and more readily portable it becomes.

I claim:—

1. A rapid fire gun including a frame 90 having a forwardly extending portion and a rearwardly projecting extension, a plurality of barrels supported in the forwardly projecting portion of the frame and having downwardly swinging breech pieces, a 95 magazine superposed upon the said frame for delivering cartridges to the breeches of the several barrels, a shaft mounted transversely in the lower portion of the frame and having connections for raising and 100 lowering the swinging breech pieces of the several barrels, an operating shaft mounted transversely in the rearward extension of the frame, a plurality of breech blocks for the several barrels slidably 105 disposed below the said magazine, connections between the said operating shaft and the several breech blocks, a pair of intermediate shafts mounted in parallel relation within the frame, a firing pin extending axially 110 through each of the said breech blocks, a plurality of hammers mounted upon one of the parallel shafts for movement against the firing pins and adapted to be retracted by the rearward movement of the breech blocks, 115 a plurality of dogs for holding the hammers in rearmost position, mounted upon the other parallel shaft, an arm secured to the outer end of the last mentioned shaft, main springs for actuating the several hammers, 120 a rod pivotally connected to said shaft and extending rearwardly, an operating lever secured to the operating shaft and having an upper engaging nose for contact with the rear end of the said rod whereby to rotate 125 the dogs out of engagement with the hammer, and a rod pivotally connecting the said operating lever with the first mentioned shaft for controlling movement of the breech pieces. 130

2. A rapid fire gun comprising a frame, a plurality of barrels supported in the frame and having downwardly swinging breech pieces, a shaft mounted in the frame and having connections for controlling the movements of the several breech pieces, a magazine for feeding cartridges supported in the frame, a plurality of breech blocks for feeding the cartridges into the breeches, an operating shaft, connections between the said shaft and the breech blocks for controlling the latter, an operating lever secured to the operating shaft, a connection between said lever and the first named shaft, 10 firing pins carried by the breech blocks, a plurality of spring actuated hammers for movement against the firing pins, a controlling shaft for the several hammers having means thereon to hold the hammers in 15 inoperative position against the tensions of their springs, and means whereby to actuate the said hammer controlling shaft from the operating lever to release the same.
3. A rapid fire gun comprising a frame, a plurality of barrels supported in the frame and having hinged breech pieces, a shaft mounted in the frame and having connections for controlling the movements of the several breech pieces, a magazine for 20 feeding cartridges supported in the frame, a plurality of breech blocks for feeding the cartridges into the breeches, an operating lever having connection with the first named shaft controlling the breech pieces, firing pins carried by the breech blocks, a plurality of hammers for movement against the firing pins, connections for actuating the several breech blocks from the said operating lever, and connections for controlling 25
- the several hammers from the said operating lever.
4. A rapid fire gun comprising a frame, a plurality of barrels supported in the frame and having hinged breech pieces, a magazine supported in the frame for feeding cartridges, a plurality of breech blocks for feeding cartridges into the breeches, an operating shaft, connections between the said shaft and the breech blocks for controlling the latter, an operating lever secured to the operating shaft and having 30 connections controlling the said breech pieces, firing pins carried by the breech blocks, a plurality of spring actuated hammers for movement against the firing pins, and connections for controlling said hammers from the said operating lever.
5. A rapid fire gun comprising a frame, a plurality of barrels supported in the frame, and having hinged breech pieces, a cartridge magazine supported in the frame, a plurality of breech blocks for feeding cartridges into the breeches, an operating lever having connections controlling the movement of said breech pieces and the said breech blocks, firing pins carried by the breech blocks, spring actuated hammers for movement against the firing pins, a controlling shaft for the several hammers having means thereon to hold the hammers in 35 inoperative position against the tensions of their springs, and means whereby to actuate the said hammer controlling shaft from the said operating lever.
